DESIGN FOR A DECORATIVE BADGE

Milton Tucker, Sunnyside, Long Island, N. Y.

Application January 14, 1941, Serial No. 98,036

Term of patent 3½ years

To all whom it may concern:

Be it known that I, Milton Tucker, a citizen of the United States and a resident of Sunnyside, in the county of Queens, Long Island, New York, with a post-office address in care of the Etched Products Corporation, Queens Boulevard and 39th Street, Long Island City, New York, have invented a new, original, and ornamental Design for a Decorative Badge, of which the following is a specification, reference being had to the accompanying drawing, forming part thereof, in which—

I claim:

The ornamental design for a decorative badge, as shown.

MILTON TUCKER.
